UNITED STATES PATENT OFFICE.

FRANK A. YOUNG, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 869,039.

Specification of Letters Patent.

Patented Oct. 22, 1907.

Application filed July 22, 1905. Serial No. 270,833.

To all whom it may concern:

Be it known that I, FRANK A. YOUNG, a citizen of the United States, and a resident of Syracuse, in the county of Onondaga and State of New York, have invented 5 certain new and useful Improvements in Type-Writing Machines, of which the following is a specification.

My invention relates more particularly to the paper feeding mechanism of typewriting machines and has for its main object to provide an improved device for 10 enabling paper, and more especially envelopes, cards, stiff paper, etc., to be guided against the platen and held in close contact therewith, and so that the work-sheet may be written upon close to the top and bottom edges.

15 My invention also relates to printing point indicators and to line guides.

To these and other ends, the invention resides in certain features of construction, combinations of devices and arrangements of parts to be hereinafter more fully 20 set forth and particularly pointed out in the claims.

In the accompanying drawings, Figure 1 is a fragmentary vertical sectional view, taken about centrally of the machine and from front to rear thereof, and showing so much of said machine as is necessary to a clear 25 understanding of my invention. Fig. 2 is a fragmentary front elevation of the upper portion of the machine, showing certain parts not shown in Fig. 1, and omitting other parts shown in said figure. Fig. 3 is a perspective view of the combined card guide or holder, printing 30 point indicator and line guide. Fig. 4 is an enlarged top plan view of my device shown in Fig. 3 and illustrating my improved card guide and holder and its supporting bracket. Figs. 5 and 6 are enlarged detail views showing the means for regulating the pressure of 35 the card holder or guide. Fig. 7 is an enlarged fragmentary detail view showing the mode of coöperation between the card holder, etc., and the marginal paper 40 guide or finger.

The invention is shown as applied to a machine having the general characteristics of the Monarch type-writer, but it is to be understood that said invention may be adapted to other forms of writing machines.

In the drawings, corner posts 1 of the machine support a top plate 2 which sustains brackets 3 to which 45 latter are secured top and bottom guide rails 4. Anti-friction balls 5 coöperate with the rails 4 and also with a grooved back bar 6 of a platen carriage 7 wherein is rotatably mounted a cylindrical platen 8, which may be moved longitudinally step-by-step in the printing 50 direction and line spaced and returned in a known manner.

At the front of the platen, secured to arms 9, fixed to the platen carrier, is a scale bar 10 provided with two scales, the scale along its upper edge being the platen

scale and the scale along its lower edge being the carriage scale. 55

A rod 11 is supported in the sides of the platen carrier, and slidably mounted on said rod are side or margin guides or paper fingers 12 which move with the platen and are adapted to control the side edges of the paper. 60 The end of each margin guide or paper finger 12 is bent forwardly and formed with a double cam 13 for a purpose presently to be explained.

A support or bracket comprising end or side members 14, joined by a cross bar 15, is secured centrally of the machine to the under side of the top plate by means of screws 16 which pass upward through perforations in the cross bar 15 of the bracket and take into threaded perforations in the top plate. The front edges of the side members or portions 14 are formed with depressions or 65 recesses 17 and secured in these recesses by screws 18 (as seen in Figs. 1 and 2) is a vertically disposed bracket 19 which guides and supports a ribbon vibrator 20. The ribbon vibrator normally maintains the ribbon 70 below the printing line and is connected with a known construction of vibrating mechanism (not shown), whereby said vibrator is moved upward in the guide 19 at printing operation to interpose the ribbon between the printing point on the platen 8 and any one of a series of type bars 21, only one of which is shown in the 75 drawings. The type bars are arranged in a segment of a circle below the platen and may be pivotally supported at 22 in a segmental type bar support 23 and connected by a link 24 with a known construction of type bar actuating mechanism. 80

A short rod 25 has its ends secured in the side portions 14 of the central stationary support or bracket and mounted upon this rod is a device 26, which, for convenience of description, will be hereinafter referred to usually as a card holder or pressure device; but it 90 will be understood also from the following description that this device 26 is so made that it serves not only as a card holder but as a printing point indicator and as a line guide. The said contrivance 26 is preferably formed of sheet metal in one piece and comprises a horizontally disposed cross bar 27 from which extend upwardly two arms 28 and from which extends downwardly at the right hand side a short lug 29, the inner edge of which is beveled, as indicated at 30. The upwardly extending arms 28 terminate in side portions 100 or wings 31, the outer sides of which are inclined upwardly and inwardly or formed with cam-like edges 32. The inner edges of the side portions 31 are bent outwardly towards the front of the machine, as indicated at 33. Scale marks or graduations are provided at 34

105 on the upper portions of the wings 31 on the side of the operator. Midway between the upwardly extending arms 28 the cross bar 27 is provided with an upwardly

and rearwardly extending indicator or pointer 35, which is adapted to co-operate with the carriage scale at the bottom of the scale bar 10. The ends of the cross bar 27 of the card holder are bent rearwardly, 5 forming tabs or ears 36, which are perforated at 37 for the passage of the rod 25 which pivotally supports the card holder in the machine. A coiled spring 38 surrounds the rod 25 and has one end bearing against the cross piece 15 of the central bracket and the other end 10 bearing against the cross bar 27 of the card holder 26, below the pivot rod 25, as best appears in Fig. 1. The coiled spring 38 constantly tends to press the upper part of the card holder or guide against the front face of the platen 8.

15 39 is a horizontally disposed locking lever which at its rear end may be arranged upon one of the fastening screws 16 or may be provided with a separate pivot. The forward end of said lever 39 extends through a hole 40 in the ribbon guide bracket 19. The right-hand 20 edge of the locking lever 39 is shouldered or cutaway at 42, forming a corner which co-acts with the beveled edge 30 on the card guide and the portion 43 of the lever projecting through the hole 40 serves as a finger piece for moving the lever about its pivot. As indicated in 25 Fig. 1, the lever may be provided with a downwardly extending pin 44 which may be employed in lieu of the part 43 for moving the said lever.

The card holder or guide, it will be observed, is fixed centrally of the machine, being pivotally supported on 30 the rod 25 and is positioned between the ribbon vibrator and its guide on the one side and the platen on the other, the arrangement being such that the normal operation of the platen and the ribbon vibrator are not interfered with. When the latch or lever 39 is in the 35 position shown in Figs. 2, 4 and 5, the pressure device or card guide is pressed against the platen only by the spring 38 and when so pressed, serves to exert a gentle pressure which is sufficient to assist in the feeding of ordinary paper or the like. In this position it will be 40 noted that the lever 39 stands out of contact with the arm 29 of the card guide or holder, as best appears in Fig. 5. This figure and the companion Fig. 6 show the pivoted latch or lever 39 in top plan and show a section of the card guide or holder taken on a plane 45 represented by the line x in Fig. 3. When it is desired to write upon cards, envelopes, thick paper or the like, the latch or lever 39 is swung rightwardly about its pivot from the position indicated in Fig. 5 to that indicated in Fig. 6. When the lever is thus shifted, 50 the shouldered portion 42 engages the beveled edge 30 of the lug 29 and cams the latter outward or towards the operator, thereby causing the upper part of the card guide, in contact with the platen, to be brought into and maintained in positive or locked engagement with 55 the latter.

The card a or other substance to be written on is introduced into the machine and fed around the platen by means of the usual mechanism. The card is guided and held near its side edges by the marginal guides or 60 fingers 12, but there is always a tendency more or less marked of the card to stand away from the platen or "buckle", as it is called, between the margin guides, and this tendency is particularly pronounced when the top or bottom of the card is at or in the vicinity of the 65 printing point. This "buckling" is increased as the

distance between the margin guides is increased, the space between the guides usually depending on the length of the card and that of the line to be written thereon. To prevent the "buckling" and to hold the card firmly against the platen at the printing point is 70 one of the objects of this invention, there being sufficient give or spring in the pressure device to permit of the passage of the work sheet between the platen and the device, while at the same time the positive pressure on the device forces the work sheet close 75 against the platen, causing it to conform to the curvature of the platen at the printing point and thus avoiding any shadowing of the type impressions.

The pressure device 26, it will be observed, is, in effect, a lever frame or a three-armed lever fulcrumed 80 on the rod 25 and having one of its arms, the lug 29, extending downwardly and the other arm, which is a two-part arm comprising the parts 28 and the associate parts 31 extending upwardly. When the locking lever 39 is moved from inoperative to operative or locking position, it swings the lower arm of the lever 26 outward. The upper arm of the lever or lever frame 26, however, is already in contact with the platen against which it is pressed with a comparatively gentle force by the spring 38. The result of the outward movement of the 90 lower arm of the lever or pressure device 26 is to press the upper part of the lever with still greater force against the platen. When locked by the locking lever 39 the upper ends of the pressure device or lever 26 are prevented from moving by the platen and the lower 95 part or arm 29 is prevented from moving by the shoulder 42 of the locking lever 39. The only way that the paper or card can pass between the platen and the pressure device is by the latter itself yielding or giving between the upper ends of the wings 31 and the lower 100 ends or roots of the parts 28. In order, therefore, to permit of the feeding of the paper between the pressure device and the platen the internal structure of the pressure device must be altered or changed.

The employment of the pressure device in conjunction with the side or margin guides while of course preferable, is not essential and the invention may be used separately and apart from the side guides. The pressure device 26 is so arranged that its upper ends exert a pressure against the surface of the platen towards its axis and such that though the card be quite thick and resilient it may be written upon even at the extreme edge of the top (Fig. 1) or of the bottom (Fig. 2), in which last position it will be observed the writing occurs after the bottom edge has escaped or passed 110 from beneath the upper edge of the scale bar 10. The scale bar 10 ordinarily serves to hold the card against the platen and it would spring away from the surface of the latter after passing from beneath the scale bar but for the restraining influence of the card guide. If 115 while the pressure device or card guide is thus positively maintained locked in engagement with the platen, a movement of the platen carrier across the top plate brings either of the margin guides 12 in contact with the side portions 31 of the card guide, the cam face 13 of the margin guide 12, contacting with the side portions 31, will bend or cam the associate arms 28 in succession forwardly away from the platen far enough to permit the margin guide 12 to readily move past. The co-action between the parts is repre- 120 125 130

sented in Fig. 7. It will be noted from an inspection of said figure that while the right-hand side portion 31 and arm 28 are shown cammed forward, the corresponding left-hand parts are undisturbed. This operation of the parts is possible because though the arms 28 are both integral with the cross bar 27, said arms have sufficient spring or resiliency to permit of their being moved independently of one another, so that the cam face 13 of one of the side guides 12 will act to cam 10 one of the arms 28 away from the platen and permit it to spring back towards the platen before said cam edge 13 affects the other arm.

If the side edges of the card or work sheet *a* are so far uncontrolled by the side guides 12 as to stand away 15 from the face of the platen, said edges will, as soon as they are brought during the movement of the platen into contact with the central card guide, be forced by the latter close against the surface of the platen. This operation will be brought about by reason of the sloping 20 or inclined outer edges 32 and the outwardly or forwardly bent inner edges 33 of the central guide. The outstanding edge of the card or sheet, after contacting with one of the outer edges 32, will, during further longitudinal movement of the platen, be forced against the 25 latter by the camming action of said outer edge 32 so that the card will finally be passed properly between the central card guide and the platen without mutilation. After passing from one side of the central card guide, if the card should again spring away from the 30 platen, the side edge will be caught by the outstanding edge 33 of the other side of the central guide and will be guided or deflected back against the platen and pass on, parallel with the card guide and between it and the platen.

35 The upper edges 41 of the guide or pressure device 26 are arranged preferably adjacent the lower edge of the printed line so that said edges serve as a line indicator or guide, and the scale marks 34 at said upper edges register with the platen scale on the upper edge 40 of the scale bar 10, and may be used as a platen scale, while the narrow space between the inner edges 33 of the guide, which space is indicated in the drawings by the reference numeral 45, accurately indicates the printing point on the platen.

45 The member 26 may be regarded apart from its paper controlling functions and solely as an indicating device for indicating the printing point or for indicating or finding the printing line or for serving as a platen scale or for exercising these indicating functions 50 jointly. When it is desired to make a correction on the work sheet which has been already written and removed from the machine, the work sheet may be replaced in the machine and fed around the platen in the usual way until the bottom of the line in which the correction or change is to be made registers with the elongated edges 41. The sheet may then be adjusted laterally, or longitudinally of the platen, until the letters in the line register with the graduations or scale marks 34 at the upper portion of the member 26. The platen 55 may then be moved longitudinally until the point where the correction or insertion is to be begun is in register with the space or opening 45 between the edges 33. An insertion may then be printed with the result that the letters will be in proper position. The indicating devices provided by the member 26 for finding

the line, adjusting the printed line in proper register laterally and for finding the proper point in said line have the advantage of all being in close proximity to the place where the adjusting, finding and arranging is performed, and therefore enable this adjustment to 70 be done with great accuracy.

The locking lever may be maintained in operative position when ordinary paper is to be written on, although the strong pressure provided by the locking lever is not absolutely necessary and the pressure given 75 by the spring 38 would be sufficient for such ordinary work. For some classes of work, however, notably work in which provision is made for writing a number of copies simultaneously by interposing carbon sheets between the work sheets, the locking lever 39 should 80 be swung leftward to release the pressure device, as otherwise there would be a tendency to smudge the sheets, owing to the strong pressure against the carbons.

It will be noted that I have provided a pressure device for guiding, controlling, feeding and holding the 85 card or work sheet in contact with the platen at and near the printing point; that I provide means for forcing the pressure device into a positive or locked engagement with the platen and for maintaining the pressure device and platen in said relation, there being 90 sufficient spring or give in the pressure device to permit of the passage of the work sheet between the platen and the pressure device during the back and forth movements of the platen; that the pressure device is fixed during the operation of the machine and serves 95 to hold the paper against the platen while the platen and paper are traveling; that the arrangement is such that the relatively fixed pressure device does not interfere with the traveling, margin guides or side means for holding and guiding the paper; that the pressure 100 device comprises two resilient independent fingers, each composed of a spring arm 28 and a side portion or ear 31, which side portion has an inside and an outside camming edge; and that the device has indicating functions also.

105 While for the sake of brevity the invention has been frequently referred to herein as "a card holder", "card guide", etc., it is to be understood, of course, that the invention is applicable not only to cards but to any other form of work sheet, such as envelopes, paper and 110 the like; and also that the device may in one sense be regarded as an indicating device.

Various changes in the details of construction and in the arrangement of the parts may be effected without departing from the scope of my invention.

115 What I claim as new and desire to secure by Letters Patent, is:—

1. In a typewriting machine, the combination with a platen, of a card holder mounted yieldingly and normally pressing against the platen or the paper thereon, and 120 means normally inactive but adapted to act on the card holder for increasing the pressure thereof upon the platen or the paper thereon.

2. In a typewriting machine, the combination with a platen, of a card holder, a spring acting to press the card holder normally against the platen, and a device adapted to be moved to act on the card holder to increase its pressure against the platen.

3. In a typewriting machine, the combination with a platen, of a pivoted card holder, a spring acting to press the same against the platen, and a device for increasing the pressure of the card holder and simultaneously preventing motion thereof about its pivot.

4. In a typewriting machine, the combination of a platen; a card holder; a spring tending constantly to press said card holder against said platen; and means for positively maintaining said card holder against the platen.
5. In a typewriting machine, the combination of a platen, a card holder; a spring tending constantly to press said card holder against said platen; means for positively maintaining said card holder against the platen; and means for releasing said card holder from said positive means.
6. In a typewriting machine, the combination of a longitudinally movable platen; a pressure device for paper or cards mounted on the machine frame; and means for positively maintaining the pressure device in contact with the platen.
7. In a typewriting machine, the combination of a longitudinally movable platen; a card holder pivoted to a fixed part of the machine; and means for positively maintaining said card holder in contact with the platen.
8. In a typewriting machine, the combination of a longitudinally movable platen; a card holder pivoted to a fixed part of the machine; a spring constantly tending to press said card holder against the platen; and other means which positively maintain said card holder against the platen.
9. In a typewriting machine, the combination of a longitudinally movable platen; a card holder pivoted to a fixed part of the machine; a spring constantly tending to press said card holder against the platen; means for positively maintaining said card holder against the platen; and means for releasing said card holder from said positive means.
10. In a typewriting machine, the combination of a platen, a scale for holding the paper against the platen below and parallel to the printing line; marginal paper guides for controlling the paper at its side edges, said paper guides being movable with the platen; an independent pressure device for the paper mounted to a fixed part central of the machine and acting close to the printing point; and means for positively maintaining said pressure device in engagement with the platen, said pressure device being sufficiently resilient to allow of the passage of the paper between it and the platen.
11. In a typewriting machine, the combination of a platen, a scale for holding the paper against the platen below and parallel to the printing line; marginal paper guides for controlling the paper at its side edges, said paper guides being movable with the platen; an independent pressure device for the paper mounted to a fixed part centrally of the machine and acting close to the printing point; means for positively maintaining said pressure device in engagement with the platen, said pressure device being sufficiently resilient to allow of the passage of the paper between it and the platen; and means for releasing said pressure device.
12. In a typewriting machine, the combination of a platen; a scale for holding the paper against the platen below and parallel to the printing line; marginal paper guides for controlling the paper at its side edges, said paper guides being movable with the platen; an independent pressure device for the paper mounted to a fixed part centrally of the machine and acting close to the printing point; means for positively maintaining said pressure device in engagement with the platen, said pressure device being sufficiently resilient to allow of the passage of paper between it and the platen; means for releasing said pressure device; and a spring constantly tending to press said pressure device against the platen.
13. In a front-strike typewriting machine, the combination of a platen; a centrally arranged card guide attached to a stationary part of the machine; and means for positively maintaining said card guide in contact with said platen.
14. In a front-strike typewriting machine, the combination of a platen; a centrally arranged card guide attached to a stationary part of the machine; means for positively maintaining said card guide in contact with said platen; and means for releasing said card guide from said last named means.
15. In a front-strike typewriting machine, the combination of a platen; a centrally arranged spring-pressed card guide pivoted to a stationary part of the machine; and means for positively maintaining said card guide in contact with said platen.
16. In a front-strike typewriting machine, the combination of a platen; a platen scale; a device arranged in the vicinity of the printing point and adapted to control the lower edge of a card after it leaves the control of the platen scale; and means for maintaining said device positively in contact with the platen, said device being sufficiently resilient to permit of the passage of a card between the platen and the device.
17. In a typewriting machine, the combination of a platen; means for holding and guiding the paper near its side edges, said means being movable with the platen; fixed means for guiding and holding the paper near the printing point; and means for positively maintaining said fixed means in engagement with the platen.
18. In a typewriting machine, the combination of a platen; means for holding and guiding the paper near its side edges, said means being movable with the platen; fixed means for guiding and holding the paper near the printing point; means for positively maintaining said fixed means in engagement with the platen; and means for releasing said fixed means from the control of said last named means.
19. In a typewriting machine, the combination of a platen; means for holding and guiding the paper near its side edges, said means being movable with the platen; fixed means for guiding and holding the paper near the printing point; and means for positively maintaining said fixed means in engagement with the platen, said fixed means being adapted to be acted upon by said holding and guiding means which move with the platen and thus enable the last mentioned means to pass by the fixed means.
20. In a typewriting machine, the combination of a platen; marginal paper fingers mounted to move with the platen; a fixed central paper or card holder; and means for locking said paper or card holder in a fixed position so as to maintain it positively in engagement with said platen, said card holder being movable transversely of the platen by said paper fingers.
21. In a typewriting machine, the combination of a platen; marginal paper fingers; a fixed central card guide; and means for positively maintaining said guide in engagement with the platen, said guide being sufficiently yielding to permit either of said marginal paper fingers to pass from one side to the other of it.
22. In a typewriting machine, the combination of a platen; marginal paper fingers; a fixed central card guide; and means for positively maintaining said guide in engagement with the platen, said guide being adapted to be cammed away from the platen by either of said marginal paper fingers.
23. In a typewriting machine, the combination of a platen; a plurality of guide fingers attached to a fixed part of the machine; and means for positively maintaining said guide fingers in engagement with the platen.
24. In a typewriting machine, the combination of a platen; a plurality of resilient guide fingers attached to a fixed part of the machine; and means for positively maintaining said guide fingers in engagement with the platen.
25. In a typewriting machine, the combination of a platen; a pressure device provided with camming edges, which edges are adapted to act on the sides of the paper or card; and means for positively maintaining said pressure device in contact with the platen.
26. In a typewriting machine, the combination of a platen; a pressure device for the paper or cards provided with a scale and with camming edges, which edges are adapted to act on the sides of the card or paper; and means for positively maintaining said pressure device in contact with the platen.
27. In a typewriting machine, the combination of a platen; a pressure device for paper or cards attached to a stationary part of the machine and provided with lateral camming edges adapted to act on the side edges of the paper or card; and a margin or side guide for the paper movable with the platen and provided with a cam adapted

- to act on said pressure device to move it sufficiently to permit said margin guide to pass.
28. In a typewriting machine, the combination of a platen; a pressure device formed of sheet metal and provided with a pair of paper holding fingers each independently yieldable and each having side edges adapted to control the paper, the printing point on the platen being indicated by an opening between the inner edges of the fingers, the printing line being indicated by the tops of the 10 fingers; and a scale formed on the upper portions of said fingers.
29. In a typewriting machine, the combination of a platen; a platen scale, and a pressure device of sheet metal formed with a pair of independently yieldable paper 15 fingers having camming edges and also provided with a pointer adapted to coöperate with the carriage scale, said pressure device being adapted to serve as a printing point indicator, a printing line indicator, and a platen scale.
30. In a typewriting machine, the combination of a 20 platen; a sheet metal pressure device having a pair of independently yieldable paper fingers formed with camming edges, said pressure device being pivoted to a stationary part of the machine; a spring constantly tending to press said device against the platen; and a locking lever for 25 positively maintaining said device against the platen.
31. In a typewriting machine, the combination of a platen; a sheet metal pressure device having a pair of independently yieldable paper fingers formed with camming edges, said pressure device being pivoted to a stationary 30 part of the machine; a spring constantly tending to press the ends of said paper fingers against the platen; and a pivoted lock or latch adapted to act on said pressure device to positively maintain the ends of said paper fingers against the platen.
32. In a typewriting machine, the combination of a 35 platen, a carriage scale and a device fixed to the framework opposite the printing point and adapted to serve as a platen scale, a line indicator, a printing point indicator and a carriage scale indicator.
33. In a typewriting machine, the combination of a 40 platen, a device adapted to serve as a platen scale and a line indicator, and means for locking said device in engagement with the platen.
34. In a typewriting machine, the combination of a 45 platen, a device adapted to serve as a platen scale, a line indicator and a printing point indicator, and means for locking said device in engagement with the platen.
35. In a typewriting machine, a sheet metal device 50 fixed to the framework opposite the printing point and adapted to serve as a combined line indicator, platen scale and printing point indicator.
36. In a typewriting machine, a sheet metal device 55 fixed to the framework opposite the printing point and adapted to serve as a combined line indicator, platen scale, printing point indicator and carriage scale indicator.
37. In a typewriting machine, the combination of a platen and a sheet metal device fixed to the framework opposite the printing point and adapted to serve as a combined line indicator, platen scale and printing point indicator, said device being maintained in constant engagement with the platen. 60
38. In a typewriting machine, the combination with a platen, of a card holding device pivoted to the machine frame and constructed to serve as a line guide and also as a printing point indicator. 65
39. In a typewriting machine, the combination with a carriage, a platen and a platen scale, of a card holding device pivoted to the machine frame and maintained by pressure in contact with the platen or the paper thereon, said card holding device serving also as a line guide, a 70 printing point indicator and as a carriage scale pointer.
40. In a front-strike typewriting machine, the combination with a platen, of an upstanding pressure device pivoted at its lower portion centrally of the machine and bearing against the platen at its upper edge. 75
41. In a front-strike typewriting machine, the combination with a platen, of an upstanding pressure device pivoted at its lower portion centrally of the machine and bearing against the platen at its upper edge, and a device for locking the pressure device against movement on its pivot and simultaneously increasing the pressure of its upper edge against the platen. 80
42. In a typewriting machine, the combination of a platen, a paper or card holder made of resilient material, a spring for maintaining said holder against the platen 85 under gentle pressure, and means independent of said spring for at will exerting a stronger pressure on said holder than said spring exerts.
43. In a typewriting machine, the combination of a platen, a pivoted card holder, the upper portion of which 90 coöperates with the platen, a spring for causing said upper portion to act with a gentle pressure, a device connected with said card holder and arranged on the opposite side of the pivot thereof, and means acting on said device to cause the upper portion of the card holder to bear with 95 stronger pressure against the platen.
44. In a typewriting machine, the combination of a platen, a pivoted spring-pressed resilient paper or card holder made in the form of a lever and having a lug or projection below the pivot, and a hand lever constructed to engage said lug or projection to clamp the card holder and exert an increased pressure of its upper portion against the platen. 100

Signed at Syracuse, in the county of Onondaga, and State of New York, this 20th day of July A. D. 1905.
